FIG. 1

FIG. 1 is a side perspective view of a combined bun and frankfurter showing our new design;

FIG. 2 is a fragmentary side elevation of another embodiment showing the features of an ear and mouth on the bun portion thereof;

FIG. 3 is a side perspective view of a third embodiment thereof as it appears with the frankfurter positioned in a slit in the bottom of the bun and stopping short of the front thereof;

FIG. 4 is a side perspective view of a fourth embodiment showing the frankfurter positioned in a slit on the top of the bun and stopping short of the front;

FIG. 5 is a side perspective view of a fifth embodiment thereof as it appears with the frankfurter positioned within an opening in the bun and projecting from the rear; and

FIG. 6 is a fragmentary rear perspective view of FIG. 5.

This is a division of our application Ser. No. D. 16,743, filed Apr. 14, 1969, now Patent No. D. 223,223.

The undisclosed sides of the embodiments shown in the figures above present a mirror image of the sides disclosed.

We claim:

The ornamental design for combined bun and frankfurter, as shown and described.
